UNITED STATES PATENT OFFICE.

OSCAR H. JUNG, OF MILWAUKEE, WISCONSIN, ASSIGNOR TO TRICO FUSE MFG. CO., OF MILWAUKEE, WISCONSIN, A CORPORATION OF WISCONSIN.

SHOE LUG.

Application filed March 25, 1927. Serial No. 178,465.

This invention relates to shoes and is particularly directed to a lug for use with a shoe intended primarily for athletic purposes where it is desirable to secure a firm grip upon 5 the ground.

It frequently happens that players are required to play upon ground of extreme softness, such, for example, as a muddy field and upon ground which is not so soft, and consequently do not require as large or extensive 10 lugs for their shoes as the first type of ground.

Attempts have been made to provide removable lugs for the shoes which may be substituted one for the other, but these attempts 15 have not proven wholly satisfactory, as the lugs pull off from the soles on the one hand, and also as it is difficult to secure a rigid attachment of the removable lug and at the same time permitting easy substitution of one 20 lug for another.

This invention is designed to overcome the defects noted above and objects of such invention are to provide a novel form of lug so constructed that it may be readily secured to 25 the sole of a shoe in a manner to prevent tearing off of the lug from the sole even under excessive strains, but which is secured to the sole at widely spaced points, so that the resistance to a turning moment is very great 30 indeed.

Further objects are to provide a novel form 35 of lug in which a plate-like member is rigidly secured to the sole of the shoe by prongs projecting upwardly from its edges, so that they are widely spaced and when projected into the sole and clamped thereto, provide a very 40 secure attachment for the plate at widely spaced points to thus eliminate all tearing of the lug from the sole and all relative turning of the lug with respect to the sole.

An embodiment of the invention is shown in the accompanying drawings in which:

Figure 1 is a view from the underside of the shoe equipped with the lugs.

45 Figure 2 is an enlarged sectional view on the line 2—2 of Figure 1;

Figure 3 is a sectional view on the line 3—3 of Figure 2.

Referring to the drawings, it will be seen 50 that the shoe is provided with a sole 1 to which a plate 2 is attached. This plate is preferably disc-like, although obviously other shapes could be employed. It is provided with a plurality of regularly spaced 55 integral prongs 3 extending upwardly from

its edges and passed into and clinched to the sole of the shoe, as shown in Figure 2. These prongs are at widely spaced points as is apparent from Figures 2 and 3 and, consequently, prevent any turning whatsoever of the lug 60 with reference to the sole. The plate 2 is provided with a depressed apertured portion which receives the threaded stud 4, as shown in Figure 2. This threaded stud is provided with a reduced portion 5 which is passed 65 through the aperture and is subsequently headed, as indicated at 6. It is preferably welded to the plate 2 to secure the utmost rigidity. This construction, coupled with the fact that an abrupt shoulder is formed, as indicated by the reference character 7, against 70 which the underside of the plate 2 bears, secures the maximum rigidity and strength of attachment between the stud and the plate.

The removable or interchangeable lug is 75 indicated by the reference character 8 and is preferably in the shape of a truncated cone. It is also preferable to form these lugs of fibre to secure the maximum lightness, although retaining the necessary strength. 80 The lugs are centrally apertured and may themselves be threaded, if desired. However, in the form shown, the lug is provided with a reenforcing metallic sleeve 9, internally threaded to receive the stud 4. This sleeve 85 is driven into the drilled out hole 10 in the lug and it is to be noted that its edges are slightly swaged out, as indicated at 11, to provide a plurality of gripping ears seated within the body of the lug to thus prevent loosening 90 of the reenforcing sleeve and prevent relative rotation between the sleeve and the lug. It is preferable to slightly bore out the upper end of the sleeve 9 to provide a thinned flange 95 11', as shown most clearly in Figure 3, to facilitate the formation of the ears or lugs 11. It is also preferable to provide a recessed portion in the upper face of the lug which accommodates the depressed portion of the plate 2, such depressed portion being indicated by the reference character 13, and being employed to accommodate the head 6 of the stud. The lug is provided with an annular shoulder or abrupt face 14 which, when the lug is screwed in place, firmly bears at the 100 marginal edges of the disc 2 and thus is supported from the disc along a surface spaced outwardly from the center point of the disc. Thus, the maximum resistance to turning is secured by this construction and the pin or 105 110

stud 4 is relieved of a considerable amount of strain which it would otherwise bear.

By forming the lug of fibre and the sleeve of metal a very light and strong structure is obtained and one which may be very cheaply manufactured.

Although the invention has been described in considerable detail, such description is intended as illustrative rather than limiting 10 as the invention may be variously embodied and as the scope of such invention is to be determined as claimed.

I claim:

15 The combination of a shoe, a circular plate having a plurality of integral prongs projecting from its edges and extending into the sole and clinched thereto, said plate having a recessed portion centrally apertured, a

threaded stud projecting through the aperture in the recessed portion and having a 20 head seated within the recessed portion, and a removable lug of truncated conical contour having a reenforcing sleeve provided with a threaded aperture for the reception of said stud and having a centrally cut-away upper 25 portion extending a material distance radially outwardly from said stud, whereby an annular bearing surface is provided on the lug which contacts with the underside of the plate adjacent its margin. 30

In testimony that I claim the foregoing I have hereunto set my hand at Milwaukee, in the county of Milwaukee and State of Wisconsin.

OSCAR H. JUNG.
